(57) **CLAIM**

The ornamental design for a display screen with animated graphical user interface, as shown and described.

DESCRIPTION

FIG. 1 is the first image in a sequence for a display screen with animated graphical user interface showing my new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;
FIG. 9 is the ninth image thereof;
FIG. 10 is the tenth image thereof;
FIG. 11 is the eleventh image thereof;
FIG. 12 is the twelfth image thereof;
FIG. 13 is the thirteenth image thereof;
FIG. 14 is the fourteenth image thereof;
FIG. 15 is the fifteenth image thereof;
FIG. 16 is the sixteenth image thereof;
FIG. 17 is the seventeenth image thereof;
FIG. 18 is the eighteenth image thereof;
FIG. 19 is the nineteenth image thereof;
FIG. 20 is the twentieth image thereof;
FIG. 21 is the twenty-first image thereof;
FIG. 22 is the twenty-second image thereof;
FIG. 23 is the twenty-third image thereof;
FIG. 24 is the twenty-fourth image thereof;
FIG. 25 is the twenty-fifth image thereof;
FIG. 26 is the twenty-sixth image thereof;
FIG. 27 is the twenty-seventh image thereof;
FIG. 28 is the twenty-eighth image thereof;
FIG. 29 is the twenty-ninth image thereof;

FIG. 30 is the thirtieth image thereof;
FIG. 31 is the thirty-first image thereof;
FIG. 32 is the thirty-second image thereof;
FIG. 33 is the thirty-third image thereof;
FIG. 34 is the thirty-fourth image thereof;
FIG. 35 is the thirty-fifth image thereof;
FIG. 36 is the thirty-sixth image thereof;
FIG. 37 is the thirty-seventh image thereof;
FIG. 38 is the thirty-eighth image thereof;
FIG. 39 is the thirty-ninth image thereof; and,
FIG. 40 is the fortieth image thereof.

The appearance of the animated graphical user interface sequentially transitions between the images shown in FIGS. 1-40. The process or period in which one image transitions to another forms no part of the claimed design. The outermost even-length broken line and the broken line showing of the circular feature illustrate an electronic device. The uneven-length broken line at the periphery of the display screen illustrates a portion of the article. None of the broken lines form part of the claimed design.
